UNITED STATES PATENT OFFICE.

LEVI H. GOODWIN, OF CINCINNATI, OHIO.

ELEVATED RAILWAY.

SPECIFICATION forming part of Letters Patent No. 445,467, dated January 27, 1891.

Application filed January 17, 1890. Serial No. 337,203. (No model.)

To all whom it may concern:

Be it known that I, LEVI H. GOODWIN, a citizen of the United States, and a resident of Cincinnati, in the county of Hamilton and 5 State of Ohio, have invented certain new and useful Improvements in Elevated Railways, of which the following is a specification.

My invention relates to that class of elevated railways which employ single posts to 10 sustain the tramway.

The object of my invention is to provide a strong elevated-railway support upon posts which are made of double-arch form, in which 15 is located the tramway above the cars, which travels through the openings in said posts and upon the tramway.

Another object of my invention is to provide a single line of posts which will support an elevated railway, and also telegraph-poles 20 upon the top.

The various features of my invention will be fully set forth in the description of the accompanying drawings, making a part of this specification, in which—

25 Figure 1 is a side elevation of my improvement; Fig. 2, a sectional elevation on line *xx*, Fig. 1. Fig. 3 is a modified form of journaling the car-wheels. Fig. 4 is a section through one side of the archway, taken at *yy*, Fig. 1.

30 1 represents the street-pavement.

A is a concrete foundation, in which or to which the posts B are secured. The posts B are made sectional and riveted together, of octagonal or many-sided form, the sections

35 being flanged or riveted together, after the manner of constructing bridges. The tops of these posts are of double-arch form, which are made by firmly riveting to the top of the posts the sections C and D. The sections D

40 are flanged above their point of connection to the posts, and the sections C riveted firmly thereto. These sections C D are firmly riveted to the section of post B, as shown in Figs. 1 and 2. The series of posts are connected

45 together by a truss E, the upper chord of the truss being firmly connected to the top sections C by knee-braces 3, having the web 4, said braces being bolted to the post and to the top flange of the upper chord, and are further supported by brace E', passing beneath

50 the truss and being bolted to the under side of the arch, as seen in Fig. 2. The truss E

serves as a girder to connect the posts B together, as well as to sustain and distribute the weight and strain of the cars.

55

5 represents webs or braces at the bottom of the posts B under the arch. 6 represents similar webs at the top of the arch for strengthening the posts.

7 represents a socket formed on the tops of 60 the posts between the webs 6, into which is inserted a telegraph-pole 8.

9 represents tie-bars securely fastened to the bottom chord, on which are placed the track-rails G.

65

10 represents the car, which is suspended by means of stanchions 11, to which wheels 12 of the car are journaled.

65

In Fig. 3 I have shown a modification which shows a U-shaped stanchion 13 passing over 70 the car-wheels to journal the axle upon each side, and is the preferred form of construction. The car when suspended rests on springs 14, leaving a space 15 between the car and trucks. It is designed that these posts 75 be set near the edge of the sidewalk and the elevated railway occupy the space partly above the street and partly above the sidewalk. Thus a line of cars may be placed upon each side with very little obstruction to 80 the street and sidewalk traffic.

By having two tracks the car is suitably supported, and is guided by the flanges of the wheels in the ordinary manner. A strong firm elevated railway is obtained by this 85 means at comparatively small cost.

Having described my invention, what I claim is—

1. An elevated railway composed of a series of sectional posts, a double arch located on 90 top of each post, a truss for connecting said arches together, and web brackets for strengthening the same, substantially as described.

2. In an elevated railway, the combination, with a series of sectional posts B and the 95 arches supported thereby, of the truss E and the knee-braces 3 for securing the same, substantially as described.

In testimony whereof I have hereunto set my hand.

LEVI H. GOODWIN.
